US00D669758S

(12) **United States Design Patent**
Lindars et al.

(10) **Patent No.:** **US D669,758 S**
(45) **Date of Patent:** **** Oct. 30, 2012**

(54) **HUB ENCLOSURE ASSEMBLY FOR ELECTRONIC DEVICE**

(75) Inventors: **Michael Todd Lindars**, Portland, OR (US); **Jiu Chang Tang**, Nanshan District Shenzhen (CN); **George Wang**, Portland, OR (US)

(73) Assignee: **E-Business International, Inc.**, Beaverton, OR (US)

(**) Term: **14 Years**

(21) Appl. No.: **29/378,793**

(22) Filed: **Nov. 9, 2010**

(51) **LOC (9) Cl.** **08-05**

(52) **U.S. Cl.** **D8/349**

(58) **Field of Classification Search** D8/354, D8/349, 382, 384, 385, 363, 380, 499; 405/251, 405/252, 255, 230; 248/346.5; 249/83; 52/699, 250, 274, 285.2, 293.2, 293.3, 295-298, 52/708, 745.2, 745.21, 707, 170, 698, 689, 52/741.15, 378, 712; D14/126

See application file for complete search history.

(57) **CLAIM**

The ornamental design for a hub enclosure assembly for electronic device, as shown and described.

DESCRIPTION

FIG. 1 is a front view of a hub enclosure assembly for electronic device showing our new design, the broken line showing of an electronic device is for environmental purposes only and forms no part of the claimed design;

FIG. 2 is a back view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof;

FIG. 8 is a back perspective view thereof; and,

FIG. 9 is an exploded view thereof.

1 Claim, 7 Drawing Sheets
